UNITED STATES PATENT OFFICE.

WILBUR H. BENHAM, OF WATERBURY, CONNECTICUT.

DESIGN FOR A HOOK.

SPECIFICATION forming part of Design No. 34,059, dated February 12, 1901.

Application filed January 28, 1899. Serial No. 703,743. Term of patent 14 years.

To all whom it may concern:

Be it known that I, WILBUR H. BENHAM, a citizen of the United States, and a resident of Waterbury, in the county of New Haven and State of Connecticut, have invented and produced a new and original Design for a Hook, of which the following is a specification, reference being had to the accompanying drawing, forming part thereof, and in which there is shown a perspective view of a hook, showing my new design.

The hook has the same general form and is of the class used in hooks and eyes, and, as shown in the drawing, there is a shank portion a, terminating in one end with the out-turned portions forming eyes b, which lie in the same plane as the body of the shank, and about midway of the shank upturned bent portions form eyes c, arranged at substantially right angles to the plane of the shank. At the front end the shank curves upward and backward, forming the hook d, with rounded end, which when viewed in side elevation appears to terminate in the eye portions c.

The material feature of the design consists of the eyes c, located at the ends of the wire of which the hook as a whole is formed and also on opposite sides of the main portion of the shank, the said eyes being located in a plane substantially at right angles to the plane of the shank and parallel to such part and in the upward and backward curved hook terminating in the eye portion c.

Having described my invention, what I claim as new, and desire to secure by Letters Patent, is—

The design for a hook substantially as herein shown and described.

WILBUR H. BENHAM.
